UNITED STATES PATENT OFFICE.

FRANK G. DUNBAR, OF CHICAGO, ILLINOIS, ASSIGNOR TO SARGENT COMPANY, A CORPORATION OF ILLINOIS.

RAIL-ANCHOR.

1,144,532.

Specification of Letters Patent. Patented June 29, 1915.

Application filed January 7, 1915. Serial No. 904.

To all whom it may concern:

Be it known that I, FRANK G. DUNBAR, a citizen of the United States, and resident of Chicago, in the county of Cook and State 5 of Illinois, have invented certain new and useful Improvements in Rail-Anchors, of which the following is a specification.

My invention relates to rail anchors and has particular reference to a novel clamping device for use in connection therewith.

As is well known, it is common to employ devices known as rail anchors which are intended to prevent the longitudinal creeping of railroad rails, many of such devices having been heretofore suggested.

15 An object in the present construction is to provide an anchor which positively engages the rail base, and, after having once been installed, cannot become disengaged or loosened due to jar or expansion or contraction.

20 A further object is to provide an anchor which may be installed in the proper location before the clamping means are actuated; that is, so arranged that the tie-abutting shoulder may be placed rigidly against the tie and the clamping device then actuated. In this the present device distinguishes from other anchors in which the seating of the shoulder against the tie is 25 coincident with the actuation of the clamp. In such a device the adjustment is likely to be uncertain or insecure, and, therefore, undesirable.

The invention will be more readily understood by reference to the accompanying drawings in which:

Figure 1 is a side elevation of a rail anchor constructed in accordance with my invention—the device being shown in its relation 40 to a railroad tie and rail; and Fig. 2 is a plan view of the construction shown in Fig. 1.

Referring more particularly to the drawings it will be seen that my anchor is shown 45 as associated with a tie 10 and rail 11. The anchor consists in a body portion or cross bar 12 having a rail-base-engaging hook 13, a tie-engaging shoulder 14 and a clamp-holding jaw 15. Within the jaw 15 I provide an open-sided recess 16, the outside 50 wall 17 of which constitutes an extended vertical bearing for the pivot or trunnion 18 of a segment 19. This segment is provided with a toothed rail-engaged face 20, 55 this face being curved eccentrically to the

pivot 18. It will be noted that the outside edge of the pivot or trunnion 18 is straight and lies against the vertical wall 17 throughout the length of the trunnion, providing an extended bearing and eliminating 60 shear strains. The point 21 of the jaw 15 preferably overlies the rail base slightly, thus preventing the sagging of that side of the anchor. It will be noted that the trunnion 18 of the segment is located directly 65 in line, transversely, with the center of the hook 13 and also in alinement, longitudinally, with the center of the tie-abutting shoulder. The advantages arising from such construction are obvious, not the least 70 of which is that the clamping and holding forces are applied and taken up in right lines.

In practice the anchor is locked in the desired position with the shoulder directly 75 abutting the tie 10. The segment 19 is then placed in proper position and is forced by a hammer or similar instrument into tight clamping engagement, the driving force being applied at the point 22. It will be 80 seen that such a device presents many advantages, not the least of which is that of location in the desired position prior to setting the clamp.

Obviously modifications may be made in 85 the construction shown and such modifications as are within the scope of my claims I consider within the spirit of my invention.

I claim:

1. In a rail anchor the combination of a rail-engaging member having a jaw on each end thereof, one engaging the rail base, the other having a vertical recess substantially in line with the rail-engaging jaws, and a 95 segmental clamp having a pivot adapted to be seated in said vertical recess and normally held between said jaws, the rail-engaging face of said segment being toothed and curved eccentrically to the pivot of 100 the segment, substantially as described.

2. In a rail anchor, the combination of a base member having an inturned hook on each end thereof, one of said hooks being adapted to engage a rail base, and an articulate holding member pivoted in and guided between said base and one of said hooks, substantially as described.

3. In a rail anchor, the combination of a base having a rail engaging hook, an in- 110

turned flange on the other end of said base, said flange and said base being provided with a vertical recess and an arcuate clamping member having a pivot seated in said recess, said clamping member being guided between said base and said flange, substantially as described.

4. In a rail anchor, the combination of a transverse base having a rail-engaging hook, 10 an inturned flange on the opposite end of said base, said flange, in service, lying over the top of a rail base, and an arcuate clamping member pivoted in and held between said base and said flange, substantially as described.

5. In a rail anchor, the combination of a base having a rail-engaging hook on one end thereof, an inturned flange on the opposite end thereof, said base and flange being provided with registering vertical recesses and providing a vertical bearing face of substantial area, and an arcuate clamping member having a vertical pivot which is longer than the thickness of said clamping member and which pivot is adapted to bear 20

25

against said bearing surface, substantially as described.

6. In a rail anchor, the combination of a base having a rail-engaging hook on one end thereof, and an overhanging inturned flange 30 on the opposite end thereof, and an arcuate dog removably pivoted in and guided between said flange and said base, said arcuate member having a portion projecting outside the plane of the anchor and providing a striking surface for tightening said clamping member, substantially as described.

7. In a rail anchor, the combination of a base having integral jaws on both ends 40 thereof, both of which jaws are adapted to overlie the base of a rail, and an arcuate clamping member pivoted in and guided between said base and one of said jaws, substantially as described.

FRANK G. DUNBAR.
